UNITED STATES PATENT OFFICE

JOHN WASHINGTON FOWLER, OF PRINCETON, WEST VIRGINIA

FUEL SAVER FOR GASOLINE ENGINES

Application filed April 3, 1930. Serial No. 441,323.

This invention relates to attachments for intakes of gasoline engines and is particularly related to devices for saving fuel.

In the vaporization and mixing of gasoline with air to form a mixture, it has been found that a complete vaporization of the gasoline and mixture with air will give a better explosion if a small amount of moisture is present. The present invention provides a means for bringing about these results.

The primary object of this invention is the provision of an improved fuel saver.

Another object of the invention is the provision of an improved fuel saver having a heating unit to assist in completely gasifying the gasoline in the air and a moisture feeding device to supply a water content to the mixture.

Another and further object of the invention is the provision of an improved fuel saver having a heating unit, a means for supplying moisture to the mixture and a means for causing the mechanical mixing of the gas mixture.

Other and further objects of the invention will be apparent to those skilled in the art from a reading of the complete specification and claims.

In the drawing wherein I have illustrated an embodiment of my invention,

Figure 1 is a top view of my invention.

Figure 2 is an end view.

Figure 3 is a cross sectional view on the line 3—3 of Figure 2.

Referring particularly to Figure 3 where a cross section of the parts is illustrated, 10 designates the main body of the device having a chamber 11. The chamber 11 has a closure member 12 secured in place by screws 13.

A gasket member 12^a is provided to make a tight joint.

The top and bottom surfaces of the main body member 10 are plane surfaces and are adapted to fit the under surface of the intake manifold and the upper surface of the carburetor respectively. The main body 10 is constructed so as to be capable of insertion between the two normally coacting surfaces of the intake manifold and the carburetor.

The opening 14 registers with the opening in

the manifold and the opening 15 registers with the opening in the carburetor. The ears 16, with holes 16^a are provided at the upper face of the body portion 10 to secure the device to the manifold and the ears 17 with holes 17^a are provided at the bottom to register with and to be secured to the carburetor.

Within the chamber 11 and secured to one wall as by the bolts 18, is a screen 19. Extending through the wall of the main body member 10 and below the screen 19, is a heating unit 20. This heating unit 20 has a heating wire 21 which extends to terminals 22 which in turn are mounted on the insulating block 23. The wire 21 is mounted on a mica sheet and the whole is embedded in fire clay.

The block 23 is secured to the main body member 10 by the screws 24. A non-conducting gasket 25 seals the opening in the main body member 10, through which the heating unit 20 passes.

Between the screen 19 and the heating unit 20 is a filling of suitable fibrous material such as asbestos as at 25'.

An opening 26 through the wall of the main body 10 receives the threaded end of a water supply pipe 27. Within the pipe 27 is a fibrous material as a continuation of the material 25'. At the end of the pipe 27 is a suitable water reservoir 28 to supply the water to moisten the mixture. An opening 29 is provided for filling the reservoir 28.

In order to assist in the mixing operation, I provide a whirligig having a freely rotating shaft 30 between the walls of the main body member 10. This shaft carries curved blades 31 which are so shaped as to hold the current of gas and air mixture so as to turn.

This turning action assists in the mixing operation and helps deflect the mixture toward the screen to absorb the moisture.

In the wall of the main body member 10 and communicating from the outside air to the moisture laden asbestos pad 25 is an opening 32 to supply a small amount of air to assist in evaporation of the moisture in the asbestos pad 25'.

In operating, the rarification of the air in the exhaust manifold above the opening 14, causes the atmospheric pressure below the

carburetor to cause air to rush through the carburetor and through the opening 15. This air is laden with gasoline particles some of which may be in the form of minute drops suspended in the air. This more or less raw mixture first strikes the heating unit 20 which is being heated by passing electricity through the wire 21. The heat here absorbed causes complete gasification of the particles of gasoline. The mixture then passes around the end (left in Figure 3) of the heating unit 20 and moves toward the opening 14 on the way to the intake manifold.

This mixture passes the whirligig and moves the blades 31 causing the whirligig to turn. This action tends to further mix the gases which make up the mixture. At the same time, the partial vacuum in the chamber 11, causes atmospheric pressure on the outside to force a small amount of air through the opening 32. This air strikes the asbestos 25 and evaporates the moisture therein.

In addition, the water falling on or in close proximity to the heater unit 20, is further assisted in its evaporation. The evaporated moisture passes through the screen and into the mixture then in the chamber 11. After the thorough mixing in the chamber 11, the mixture with the air, gasified gasoline and evaporated water passes into the intake manifold and is used as a power fuel.

I have found my fuel saver to be particularly effective in causing a complete mixture between the gasified gasoline, air and water vapor which results in a saving of gasoline.

While I have illustrated and described in detail an embodiment of my invention, I desire to have it understood that the showing and description are merely illustrative, that I do not limit myself to the details of such showing and description and that modifications and changes may be made without departing from the spirit of the invention and within the scope of the appended claims.

Having described my invention what I claim and desire to secure by Letters Patent is:—

1. A fuel saver for gasoline engines comprising a body portion, a carburetor connection, an intake connection and a heater directly in the path of travel between the two connections so that the gases impinge upon the heater.

2. A fuel saver for gasoline engines comprising a body portion, a carburetor connection, an intake connection, a heater directly in the path of travel of the mixture carburetor from the carburetor and means for delivering water moisture to the heater.

3. A fuel saver for gasoline engines comprising a body portion, a carburetor connection, an intake connection, a heater in the path of travel of the mixture from the carburetor, water moisture evaporating means adjacent the heater and a connection from

the outside air through the evaporating means whereby air is drawn to assist in the evaporation of the water.

4. A fuel saver for gasoline engines comprising a body portion, a carburetor connection, an intake connection, a heater in the path of travel of the mixture, from the carburetor, a screen adjacent the heater and with the heater forming a pocket, a fibrous material in the pocket and a conduit means for delivering water to the fibrous material. 70 75

5. A fuel saver for gasoline engines comprising a body portion, a carburetor connection, an intake connection, a heater in the path of travel of the mixture, means for evaporating water moisture and a whirligig for mixing the gas and air mixture. 80

6. A fuel saver for gasoline engines comprising a body portion, a carburetor connection, an intake connection, a heater in the path of travel of the mixture from the carburetor, a screen adjacent the heater and with the heater forming a pocket, a fibrous material in the pocket for evaporating water, a duct, means for delivering water to the fibrous material, an air duct for delivering air to the fibrous material and a whirligig for assisting in the mixing operation. 85 90 95
